UNITED STATES PATENT OFFICE

WALTER J. ANDING, OF COLUMBUS, OHIO

CUSHION MEANS FOR SHOE SHANKS

Application filed February 23, 1929. Serial No. 341,884.

This invention relates broadly to shoes, and with reference to the more specific features thereof the invention has particular application to the shank construction of shoes. Most shoes have the shank portions thereof constructed to include resilient metallic stiffening elements which serve in use to maintain the several parts of the shoe in properly related order. The presence of these shank stiffeners produces a shoe construction which tends often to injure the foot of the wearer. In other words, the rigid construction afforded by the metallic stiffener does not provide for the free and natural flexure of the bones of the foot comprising the meta-tarsal arch with the result that shoes frequently fatigue the feet of the wearer and in many instances prove positively injurious.

It is therefore the primary object of the present invention to provide in a shoe having a metallic shank stiffener an improved form of cushion which consists of a soft, pliable and compressible material such as sponge or gum rubber, and wherein the cushion is shaped generally to conform to the outline of the shank stiffener, the said cushion being carried upon the upper surface of the stiffener between the insole and outsole of the shoe and in registration with the meta-tarsal bone structure of the foot.

In the formation of a shoe with the present invention the cushion extends longitudinally of the shoe shank above the stiffener and between the insole and outsole and the last about which the shoe is formed is provided with a longitudinally extending groove along its shank surface, whereby when a shoe is completed the cushion produces a ridge which extends lengthwise of the shoe shank and which projects above the insole, the arrangement being such that the cushioned ridge will enter the hollow of the foot, cooperative with the meta-tarsal bone structure and support and maintain the latter in proper positions of articulation during the wearing of the shoe to the end of overcoming foot fatigue, fallen arches and other orthopedic deformities or conditions.

With these and other objects in view which will appear as the description proceeds, the

invention consists in the novel features of construction, combinations of elements and arrangements of parts hereinafter fully described and set forth in the appended claims.

In the accompanying drawings:

Figure 1 is a bottom plan view of a shoe with the outer sole and heel removed showing the present invention applied to the insole of the shoe,

Figure 2 is a vertical sectional view showing the lower portion of a shoe containing the present invention,

Figure 3 is a perspective view of the stiffening portion of the invention in its preferred form,

Figure 4 is a transverse sectional view of Figure 3 taken on the line 4—4 of Figure 2,

Figure 5 is a perspective view of the cushioning portion of the present invention,

Figure 6 is a perspective view of another form of the stiffening portion embodying the present invention.

Referring more particularly to the drawings, the numeral 1 designates the shank stiffener in its entirety. The numeral 2 designates the shoe to which the shank stiffener is applied and the numeral 3 designates the insole of the shoe. The shank stiffener 1 is adapted to be applied to the shoe between the insole and the outer sole and comprises a

stiffening portion 4 and a cushioning portion 5. The stiffening portion 4 is formed preferably from a single strip of spring steel and is shaped longitudinally to conform to the curvature of the shank of the shoe. The rearward or heel end 6 of the stiffening portion is formed flat with the inner portion cutaway so that the same presents a U shaped appearance for forming extensions 7 on the rearward end of the stiffening portion. This

permits the shank stiffener 1 to be positioned on the insole 3, as shown in Figure 1, so that the rearward end 6 of the stiffening portion is against the heel portion 8 of the insole with the extensions 7 positioned on either side of the central portion 9 of the heel 8.

The stiffening portion, being a comparatively narrow strip of material, the rearward end 6 thereof covers only a small portion of the surface of the heel 8 and leaves entirely

unobstructed the marginal portion 10 of the heel as well as the central portion 9. The intermediate portion 11 of the stiffening portion is formed with a concavity or depression which serves to reinforce and stiffen the same throughout its intermediate portion so that by this construction sufficient strength and stiffness is imparted to a relatively thin material thus making possible the successful 10 use of shank stiffeners in shoes where the soles are made of relatively thin material. This is especially important in the manufacture of feminine footwear, where because of the thinness of the materials and the nature 15 of the articles manufactured, bulkiness must be avoided. My device imparts the requisite strength and flexibility without increasing the apparent thickness of the shoe.

The stiffening portion 4 is adapted to extend over a portion of the heel 8 and throughout the entire length of the shank 12 of the sole and in its preferred form terminates in a forward end 13 which is slightly widened and extends toward the inner side of the shoe, 25 since the intermediate portion 11 and forward end 13 conform in outline to the outline of the shank portion 12 of the sole but of course, are much narrower than the sole. The forward edge 14 is shaped to conform 30 to the line on which the vamp portion 15 of the sole bends away from the shank portion 12, so that the stiffening portion while reinforcing the shank in no way interferes with the flexibility of the shoe.

35 The cushioning portion 5 is formed preferably from sponge rubber which has been rendered freely pliable and compressible and is adapted to be positioned on the upper surface of the stiffening portion 4, the material 40 on the under surface of the cushioning portion being formed to occupy the concavity or depression in the stiffening portion, so that when the shank stiffener is applied to the shoe, as shown in Figure 1, the cushioning portion 45 5 is positioned between the insole 3 and the stiffening portion 4. The cushioning portion 5 is adapted to extend throughout the shank portion of the sole so that the heel portion 6 of the stiffening portion 4 extends beyond 50 the cushioning portion. The cushioning portion 5 conforms in outline to the outline of the intermediate portion 11 and the forward end 13 of the stiffening portion, the sides of the cushioning portion extending 55 slightly beyond the sides of the stiffening portion, the forward end 16 of the cushioning portion extending slightly beyond the forward end of the stiffening portion and being 60 gradually thinned down to a rounded forward edge 17 so that when the device is applied to a shoe no abrupt surfaces will be presented.

The shank stiffener may be fastened to the 65 insole 3 by means of brads or nails 18 which

are received in holes 19 formed near each end of the stiffening portion.

The shank stiffener 1, while conforming in outline throughout its intermediate and forward end portions to the outline of the shank of the sole 12, is much narrower than the sole when the stiffener is applied to the sole, as shown in Figure 1, there remains an ample margin 20 of the sole on either side of the intermediate portion 11.

In the manufacture of the shoe the device is first applied to the insole as shown in Figure 1, the cushioning portion 5 being engaged by the insole and the stiffening portion 4. The outer sole 21 is then applied to the welt 22 which has been sewed to the insole and upper in the usual manner in making welt shoes. More frequently the heel portion of the sole is not sewed but pegged together. In either event, however, the use of my device does not obstruct any portion of the sole through which the stitching must pass. When the outer sole 21 and insole 3 have been secured together by stitching along the marginal portion 20, the soles 21 and 3 are drawn tightly about the shank stiffener 1 positioning the cushioning portion 5 against the stiffening portion 4 thus incorporating the shank stiffener into the sole of the shoe and rendering unnecessary any further fastening means to retain the shank stiffener in its position.

It will be observed that the cushioning portion 5 is positioned between the stiffening portion 4 and the insole 3, thus filling the concavity or depressed portion and covering the edges thereof so that the device throughout its shank portion presents a cushioned upper surface which increases the comfort of the shoe when worn and also causing the insole throughout its shank portion to be slightly raised and to prevent a slightly convex upper surface, thus permitting the insole on its upper surface to conform to the curvature of the bottom of the arch of the foot thereby supporting the arch comprising the meta-tarsal bones of the foot in a comfortable and efficient manner. This construction also prevents the edges of the stiffening portion 4 from coming in contact with the insole 3 so that the proper resilience may be retained in the shank without any damage or injury to the insole because of frictional contact between the insole and the stiffening portion 4. It will also be observed that when the cushioning portion 5 is constructed of soft rubber, the stiffening portion 4 throughout its intermediate and forward portion will be protected from exposure or contact with moisture caused by perspiration of the foot when the shoe is being worn.

After the outer sole 21 has been applied, the heel 22 is next fastened to the shoe. This is accomplished by means of pegs or nails driven into the marginal portion 10 of the heel seat or in the case of feminine footwear

where wooden heels are employed, the heel is usually attached to the shoe by means of a last screw 23 which passes through the central portion 9 of the sole and into the wooden heel 22 during the drying of an adhesive uniting the heel and sole. With my device this may be accomplished in the usual manner because the central portion 9 of the heel is unobstructed, the extensions 7 being on either side of the central portion. It is obvious that when the heel 22 has been attached to the shoe, the rearward end 6 is firmly positioned and held in place between the insole 3 and the outer sole 21 and above the heel so that the heel and shank portion of the shoe are resiliently braced together, the forward end 13 being somewhat widened and conforming to the line established by the bending of the vamp portion 15 from the shank portion 12 of the sole. The device thus serves to maintain the sole in its proper shape and to resist the twisting of the sole which results when the heel of the shoe becomes worn on one side and serves further to relieve the ankles from strain by maintaining the shoe in proper alignment under varying conditions of service.

It will thus be seen that the device maintains the shoe in its proper alignment and shape without in any manner substantially interfering with its flexibility and at the same time strengthens the heel and shank and maintains their proper relationship, imparting to the shank the requisite resiliency which is essential when a high wooden heel is employed.

It will be understood that while the device shown in Figure 1 is for the shoe of the left foot, the device is made both left and right. The raised portion of the insole produced by the cushion is shaped to conform to the natural arch afforded by the instep of the human foot. It will be observed that this raised portion is devoid of sharp or abrupt surfaces but is gradually grooved and blended into the plane of the insole, although the major portion of the ridge lies in planes above that of the insole. The ridge by conforming to the shape of the foot, maintains the bones comprising the meta-tarsal arch in proper order, affording relief in cases of the so-called "fallen" arch and provides generally for enhanced foot comfort in shoe construction. In the production of the shoe, the bottom of the last is grooved along its shank portion in order to admit of the formation of the raised cushion portion in the shoe. It will be observed that the rubber pad comprising the cushion is protected by the insole, and due to the material from which the cushion is formed and its encased position within the shoe itself, the life of the cushion is at least equal to that of the shoe.

What is claimed is:

1. A shank stiffener comprising a shank

portion and a stiffening portion, said stiffening portion comprising a strip of resilient and relatively thin material shaped to conform to the curvature of a shank portion of the sole of a shoe, the forward edge conforming to a line established by the bend of the vamp portion of the sole from the shank portion of the sole, the other end of said strip being U shaped and said strip intermediate of its ends being concave, and the said cushioning portion comprising a single piece of compressible material and positioned on the upper side of said stiffening portion, the under side of said cushioning portion being shaped to conform to the concavity in the intermediate portion of said stiffening portion, the sides and forward end of said cushioning portion extending beyond the sides and forward end of said stiffening portion.

2. A shank stiffener comprising a shank portion and a stiffening portion, said stiffening portion comprising a strip of thin resilient metal and positioned between the inner and outer soles of a shoe and to extend from the central portion of a heel to the junction of the sole and shank, the forward end of said strip being widened to extend toward the inner side of a shoe with the forward edge formed to coincide with the line established by the bend of the vamp portion of the sole from the shank portion of the sole, the other end of said strip being flat with the inner portion cut-away and said strip intermediate of its ends having a longitudinal depression, the said cushioning portion comprising a single piece of pliable compressible material positioned on the upper side of said stiffening portion, the under side of said material being formed for positioning within the longitudinal depression of said strip, the sides and end of said cushioning portion extending beyond the sides and forward end of said stiffening portion.

3. A shank stiffener comprising a shank portion and a stiffening portion, said stiffening portion comprising a strip of relatively thin resilient metal adapted to be positioned between the inner and outer soles of a shoe and to extend from above the central portion of a heel of a shoe to the juncture of the vamp and shank portions of a sole, the forward end of said strip being widened to extend toward the inner side of a shoe with the forward edge formed to coincide with the line established by the bend of the sole from the shank of the shoe, the other end of said strip being flat with a U shaped end edge, said strip intermediate of its ends having a longitudinal depression, said cushioning portion comprising a single piece of pliable compressible material positioned on the upper side of said stiffening portion throughout its intermediate portion and forward end, the sides of said cushioning portion extending beyond the sides of said stiffening portion, the forward end of said

cushioning portion being widened and tapered to a thin edge and extending beyond the forward end of the said stiffening portion.

4. A shoe shank stiffener comprising a resilient plate arranged to be mounted in the shank of a sole between the inner and outer soles thereof, and to extend throughout the length of the shank, and a cushion of soft, pliable and yieldable material mounted upon the upper surface of said plate and conforming approximately to the contour of the latter, said cushion being adapted to produce a longitudinally extending convex upper surface on the shank portion of the inner sole of the associate shoe.

5. In a shoe, the combination with the shank portion thereof including the inner sole and the outer sole, of a cushion of yieldable material arranged between the inner sole and outer sole and serving to produce a longitudinally extending ridge along the shank portion of the inner sole, said ridge being narrower than the shank portion of the shoe and disposed approximately centrally thereof.

6. In a shoe, the combination with the shank portion thereof including the inner and outer soles, of a shank stiffener extending throughout the length of the shank portion of the shoe and disposed between said inner and outer soles, and a cushion of a compressible resilient material having the yielding properties of soft rubber carried by said shank stiffener and conforming approximately to the shape thereof, said cushion having a convex upper surface and serving to produce a ridge along the inner sole which extends above the general plane of said inner sole.

In testimony whereof I affix my signature.
40 WALTER J. ANDING.
